United States Patent Office.

JOHN DENNIS, OF OSWEGO, NEW YORK.

Letters Patent No. 98,042, dated December 21, 1869.

IMPROVEMENT IN HAY AND GRAIN-ELEVATORS.

The Schedule referred to in these Letters Patent and making part of the same.

To all whom it may concern:

Be it known that I, JOHN DENNIS, of Oswego, in the county of Oswego, and State of New York, (at present temporarily residing at New Market, in the county of York, and Province of Ontario, Dominion of Canada,) have invented a new and useful Improvement in Hay and Grain-Elevator; and I do hereby declare that the following is a full, clear, and exact description thereof, which will enable others skilled in the art to make and use the same, reference being had to the accompanying drawings, forming part of this specification, in which—

Figure 1 is a horizontal section of the top part of the frame of a barn to which my improvement has been attached.

Figure 2 is a vertical section of the same, taken through the line *x x*, fig. 1.

Figure 3 is a detail vertical section of the same, taken through the line *y y*, fig. 1.

Similar letters of reference indicate corresponding parts.

My invention has for its object to furnish an improved device to be used in connection with my improved hay and grain-elevator, patented September 21, 1869, and numbered 95,006, for the purpose of moving the whole load of hay or grain, when elevated, to any desired part of the barn before unloading it; and

It consists in the tram-way or track, and in the guide-aprons, the whole being constructed and operating as hereinafter more fully described.

A represents the frame of a barn.

Upon the upper tie-beams of the barn, or at or about the same height as said beams, is erected a tram-way or track *B C*, the part *B* being stationary, and the part *C* that extends over the barn-floor being jointed, as shown in figs. 1 and 3, so that the said part *C* may be turned back out of the way when raising the load of hay or grain, and swung back beneath said load when it has been sufficiently elevated, and again removed or swung out of the way, to allow the empty wagon-rack to be lowered to the wagon.

The track *B C* inclines from the floor toward the outer side or end of the mow; and when there is a mow upon both sides of the floor, the stationary parts of the track may incline in both directions from said floor. In this case the movable or swinging part *C* of said track should have a reversible incline placed upon it, so that it may be made to incline in either direc-

tion, according to the side upon which the load is to be unloaded.

D is a small car, the wheels of which roll along the track *B C*, and the body of which may be made inclined, to correspond with the inclination of the track *B C*.

In case the track is made to incline in both directions, the inclined part of the body of the car *D* may be made reversible, to correspond with the inclination of either part of said track.

In case the track inclines in but one direction, the inclination of the car *D* may be obtained by making two of its wheels larger than the other two.

In using the device, when the wagon-rack and load have been raised, the movable part *C* of the track *B C* is swung into place, and the car *D* is run beneath the loaded rack. The loaded rack is then lowered upon the car *D*, which is then allowed to run down the inclined track to the desired position. The load may then be pitched into the mow by hand, or it may be unloaded bodily by checking the car suddenly, so that the acquired momentum of the load may carry it into the mow. The car and wagon-rack are then drawn back, the rack is raised from the car, the car and movable part of the track are removed, and the track lowered upon the wagon.

E are aprons or slides pivoted to the frame *A*, of the barn, upon both sides of the track *B*, which, when the middle section of the mow is filled, may be used to guide the hay or grain into any desired part of the end sections of the mow, by supporting the said aprons at the proper inclination.

Having thus described my invention,

I claim as new, and desire to secure by Letters Patent—

1. The track *B C*, constructed as described, and car *D*, in combination with the frame of a barn, when used in connection with my improved hay and grain-elevator, patented September 21, 1869, substantially as herein shown and described, and for the purpose set forth.

2. The aprons or slides *E*, in combination with the frame *A*, track *B C*, and car *D*, substantially as herein shown and described, and for the purpose set forth.

The above specification of my invention signed by me, this 15th day of September, 1869.
